KILN DRYING

Frederick W. Gottschalk and Herbert W. Angell,
Chicago, Ill., assignors to American Lumber &
Treating Co., a corporation of Delaware

Application April 18, 1942, Serial No. 439,518

4 Claims. (Cl. 34—86)

This invention relates to an improvement in apparatus for drying lumber in dry kilns.

The object of the invention is to economize on heat consumption by more fully utilizing the available heat contained in the circulating air before discharging it to the atmosphere.

Heretofore, lumber dry kilns have been built rather loosely, particularly around the doors and vents. Because of this loose construction it has been an exclusive practice to place the exhaust vents on the outlet or pressure side of the fans or circulating means so that the exhaustion of air was certain and more than sufficient. Likewise, the intake vents were situated on the intake or vacuum side of the fans or circulating means so that the intake of fresh air was possible. This was the ideal location for exhaust and intake vents as far as mere discharging and taking in air were concerned; however, having the exhaust vents on the outlet side of the fans meant that part of the newly-conditioned air was discharged from the kiln before it ever passed through the lumber pile. This meant that B. t. u.'s which were available for drying were being wasted; hence, more expensive lumber drying resulted.

It is the purpose of this invention to place both the exhaust and intake vents on the intake or vacuum side of the fans and operate them simultaneously as a single unit. It has been found that if the kiln is of fairly tight construction, intake of fresh air and exhaustion of used air on the intake or vacuum side of the fans is very easily and efficiently done by having the vents open inward. In this manner all discharged air will first have passed through the lumber pile, thus becoming thoroughly spent. By having the vents open inward, used air is virtually trapped and forced out of the kiln, and to compensate for this lost air an equal amount of fresh air enters through the intake vent.

Another purpose of this invention is to provide for heat exchangers on the outside of the kiln at the vent openings. The discharged air, although saturated and partially cooled, still has a considerable B. t. u. content and part of this can be reclaimed by the incoming cool air. The heat exchangers are preferably made up of several highly conductive metal plates that will transmit heat from the discharging hot air on one side to the incoming cool air on the other side.

The specific construction of the invention will be more fully explained in connection with the accompanying drawings, which illustrate the same in its preferred form.

Figure 1 is a vertical cross section of the kiln showing the pile of lumber inserted. The kiln and the pile of lumber are preferably circular in cross section as shown, is not limited to circular kilns and circular lumber piles but may be applied to kilns and lumber piles of any shape, rectangular or otherwise. Figure 2 is a longitudinal vertical section of the device. Fig. 3 is a section taken along line 3—3 of Fig. 1. Fig. 4 is a section taken along line 4—4 of Fig. 3. Fig. 5 is a section taken along line 5—5 of Fig. 3.

As shown in the drawings the kiln comprises the shell 1 within which the pile of lumber 2 is mounted on the truck 3 which runs on the track 4. A fan 5 is provided in the apex of the kiln and carries a baffle 6. The chamber is adapted to contain a stack of lumber 2 of generally circular cross section having its apex immediately below the fan and having a portion thereof substantially in contact with the baffle. It will be observed that the inner wall of the shell 1 and the outer wall of lumber 2 form a free path for air movement of gradually diminishing cross section. This path is located on one side of the drying chamber only, extending from the pressure side of the fan at the apex of the chamber around to the base of the carriage near the bottom of the chamber. At one side of the kiln an air inlet 7 is provided with a closure means 8. Immediately below the air inlet is an air outlet 9 provided with a closure means 10. Between the fan and the air inlet is a series of heating coils 11 which are provided with steam in any suitable manner. A heat exchange box 12 is arranged over the air inlet and air outlet having any desired heat exchange system.

The heat exchanger 12 operates as follows: The elongated box-like structure of substantially square cross section is positioned on the outside of the kiln and in communication with the inlet 7 and outlet 9 air passages. The heat exchanger is made up of flat metal sections, preferably of copper arranged side by side, with alternate sections communicating with the inlet air passages and others communicating with the outlet air passages, and with each section sealed off from its neighbors. The inlet sections 14 are closed at the outer side so that inlet air enters the heat exchanger at the bottom and leaves at the top. The outlet sections 15 are sealed at the bottom and top so that outlet air enters the heat exchanger at the side next to the kiln and leaves at the opposite side. Thus, while the two streams of air are in the heat exchanger, there

is an exchange of heat from the outgoing air to the ingoing air.

In the operation of the device air enters the inlet 8 and passes through the heating coils 11, then through the fan 5 and returns through the pile of lumber 2. The sticker openings in the pile of lumber are adjusted to provide uniform circulation of air therethrough as explained in my copending application, Serial No. 393,818, filed May 16, 1941, of which this application is a continuation-in-part. It will be observed that the baffle, the inner shell wall, the lumber, the track, and, to a certain extent, the truck upon which the lumber is mounted, all serve to direct the air uniformly through the sticker openings. The direction of movement of the air from the fan is originally substantially tangential to the wood. The baffle 6 initially serves to separate the air from the wood and prevent short circuiting of the air currents.

Part of the spent air which is passed through the lumber is trapped by the baffle or closure member 10 and is forced out through the air outlet 9 and the heat exchanger 12. The incoming fresh air, together with the remaining spent air in the kiln passes over the heating coils 11 and becomes conditioned.

Customary temperature control means may be included in the kiln and a series of them may be employed. In a long kiln independently controlled heating coils may be used in various sections of the kiln and these may be provided with separate wet and dry bulb control thermometers. The wet and dry bulb thermometers are used to control the heat input, humidifying and amount of venting in accordance with established principles.

Usually a series of fans 5 are employed. In a 124-inch internal diameter kiln the fans are preferably about 24 inch with 28 inch rims. A series of sprays 13 may be provided between the heating coils and the vents in order to add sufficient humidity to the incoming air. However, with the present system it is proper to control with great accuracy the amount of spent air discharged and fresh air admitted and therefore the steam spray may be eliminated in most operations since the bulk of the moisture required is provided by the lumber itself. In this way the present process is distinguished from the other processes in which the wastage of air was so great that moisture had to be added in considerable quantities to the drying process.

The vents for air may be controlled manually or automatically as desired.

Subject matter relating to the present disclosure is shown in my application 439,362, now Patent 2,343,310.

The foregoing detailed description has been

given for clearness of understanding only, and no unnecessary limitations should be understood therefrom.

We claim:

1. A dry kiln for treating elongated wood products comprising an elongated horizontal chamber of generally circular cross-section, at least one fan facing transversely of the chamber and located inside the apex thereof, a small baffle below and immediately adjacent the fan, means for mounting a stack of wood of substantially circular cross-section having its center below the center of the kiln with the long axis of the wood parallel with the axis of the chamber, the mounting means, the shell, and said baffle being shaped to direct the air current from the fan initially substantially tangentially of the stack of wood in a path of free air movement of gradually diminishing cross-section, an air exhaust vent in the chamber wall, an air intake vent in the chamber wall immediately adjacent the air exhaust vent and between it and the fan, and a heating coil within the chamber located in the air stream between the intake vent and the fan.

2. A dry kiln for treating elongated wood products comprising an elongated horizontal chamber of generally circular cross-section, at least one fan facing transversely of the chamber and located inside the apex thereof, a small baffle below and immediately adjacent the fan, means for mounting a stack of wood of substantially circular cross-section having the center below the center of the kiln with the long axis of the wood parallel with the axis of the chamber, the mounting means, the shell, and said baffle being shaped to direct the air current from the fan initially substantially tangentially of the stack of wood in a path of free air movement of gradually diminishing cross-section, an air exhaust vent in the chamber wall, an air intake vent in the chamber wall immediately adjacent the air exhaust vent and between it and the fan, and a heating coil within the chamber located in the air stream between the intake vent and the fan, said air exhaust vent and air intake vent respectively venting and admitting air solely by action of the circulating air stream within the chamber.

3. A kiln as set forth in claim 2, in which means are provided within the chamber which cooperate with the fan and baffle to pass air substantially uniformly through the wood.

4. A dry kiln as set forth in claim 1, in which heat exchange means are provided outside the kiln at the vent openings for transmitting heat from the discharging hot air to the incoming cool air.

FREDERICK W. GOTTSCHALK,
HERBERT W. ANGELL.
